TYPEWRITER CABINET

Arthur C. Thompson, Osage City, Kans., assignor
of one-fourth to Arthur R. Munns and one-
fourth to Leo J. Pearce, both of Olathe, Kans.

Application April 17, 1939, Serial No. 268,207

9 Claims. (Cl. 312—22)

This invention relates to articles of furniture and particularly cabinets for supporting typewriters in either an operative or inoperative, concealed position, and the primary object is to provide a specially formed fixture that combines with parts of the cabinet in special ways so that the typewriter is easily moved to such positions whereby the action of gravity thereon will assist in maintaining the leaf of the cabinet in a closed position.

This invention has for another important object the provision of a typewriter cabinet of the upright type that is equipped with means for supporting the typewriter in a horizontal position, which means cooperates with parts of the cabinet in a unique manner so that the typewriter will enter the relatively small space in the upright cabinet so that housing of the typewriter may occur without the employment of a large and objectionable piece of furniture.

A yet further object of this invention is to provide a typewriter cabinet with a specially formed fixture, the nature of which permits hanging a typewriter within a relatively narrow space when the leaf of the cabinet is in the closed position, which leaf serves to support the typewriter (when open).

Minor objects of this invention will appear during the course of the following specification, referring to the accompanying drawing wherein the preferred form only is illustrated, and wherein:

Figure 1 is a front elevational view of a typewriter cabinet embodying this invention.

Fig. 2 is a vertical sectional view through the cabinet taken on line II—II of Fig. 1.

Fig. 3 is an enlarged fragmentary detailed sectional view taken on line III—III of Fig. 2; and,

Fig. 4 is a top plan view of the fixture showing the same entirely removed from the cabinet.

The preferred embodiment of this invention, as exemplified in the accompanying drawing, indicates the manner of building a typewriter cabinet of the upright type and in the illustration, the numeral 6 designates the cabinet in general, one side of which is inclined and provided with an opening 8. This inclined side 10 extends upwardly and rearwardly from the vertical portion 12 of the normally front side of cabinet 6, and when leaf 14 is in the closed position, the inclined portion 10 presents a solid face.

Leaf 14 is pivotally mounted as at 16 at one of its edges directly to the end walls 18 of cabinet 6. A brace 20 at each end of leaf 14 is of the customary link type and the upper edge of leaf

14 has a grip 22 thereon. The edge of leaf 14 that is hingedly connected to ends 18 is specially formed to complement the contour of the edge of portion 12 of the front wall of the cabinet and when the leaf is open, the hinged edge projects into cabinet 6 a short distance.

In addition to the swingably mounted leaf 14, cabinet 6 has the usual pigeon holes 24, drawer 26, and filing drawers 28, all of which may be altered as desired in order to render the cabinet useful as a typewriter desk that is effective in small offices, homes or hotels where space is at a premium.

The fixture upon which typewriter 30 is mounted is ruggedly made of metal and includes a platform consisting of a pair of L-shaped members 32. The free end of each similar leg 34 of each member 32, is hingedly affixed to the leaf through the medium of a plate 36 that may be secured directly to the face of leaf 14 or swung thereinto as desired. Each plate 36 has a bearing 38 spaced about the upper face of leaf 14 so that legs 34 of members 32 are held in spaced relation to this face of the leaf.

Members 32 are secured together at the zone of juncture between legs 34 and legs 40 by a yoke 42. Legs 40 project perpendicularly from legs 34 and laterally therefrom to present a head 44 which serves as a bumper in a manner hereinafter set down.

Yoke 42 is arched intermediate its ends and a spring 46 has one end secured thereto. The other end of spring 46 is connected to the vertical portion 12 of the front wall of cabinet 6, below the axis about which leaf 14 turns. A bracket 48 is the medium of connection between the last mentioned end of spring 46 and the cabinet. This bracket 48 is formed to insure that springs 46 will be taut when the parts holding typewriter 30 are moved to a place where the typewriter is housed, as illustrated in Fig. 2.

When leaf 14 is horizontally disposed and the typewriter is ready for use, spring 46 will not be taut and only the weight of typewriter 30 will hold the platform consisting of members 32 in place.

A wooden foot 50 is on each member 32 near the hingedly mounted edge of leaf 14 to cooperate with plate 36 in maintaining legs 34 in their spaced position. The resilient elements 52 on the bottom of typewriter 30 rest upon legs 34 of members 32 that constitute the platform, and an anchor bolt 54 is associated with each leg 34. Anchor bolts 54 extend through openings 56 in

legs 34 and into the frame of the typewriter 30, as detailed in Fig. 3.

A bushing 58 having a reduced portion thereon to present a shoulder 60, insulates the fixture 5 from typewriter 30 so that vibration, due to manipulation of the keys, will not be transmitted to the cabinet or any part thereof directly through a metal to metal or solid connection.

As leaf 14 is swung from the position shown 10 in full lines of Fig. 2 to the inclined position exemplified by the dotted lines, the laterally extending members 40 will be moved about the axis of rotation of leaf 14 to cause head 44 to engage the inner surface of vertical wall 12. Spring 46 15 will be placed under tension and legs 34 of members 32 will lie in a substantially vertical plane because the length of members 40 is great enough to compensate for the angularity assumed by leaf 14.

20 Spring 46 is strong enough to overcome the action of gravity exerted on typewriter 30 and when the typewriter is housed, spring 46 relieves plates 36 of the weight that would normally be objectionable. Leaf 14 is held closed by the typewriter and associated elements and as it is swung to the open position, spring 46 releases its effective function of supporting the weight of the typewriter.

25 It is conceivable that modifications might be made in constructing a typewriter cabinet in accordance with this invention without departing from the spirit of the invention or scope of the appended claims.

Having thus described the invention, what is 30 claimed as new and desired to be secured by Letters Patent is:

35 1. In a typewriter cabinet of the upright type, including a housing having an open side and a leaf swingably secured at one of its edges to the 40 cabinet for movement to and from a position closing said open side, a fixture for carrying the typewriter comprising a platform overlying the leaf and extending to each side of the axis around which the leaf swings; means hingedly affixing 45 one edge of said platform to the leaf; and a spring joining the platform and the cabinet to draw the other edge of the platform against the latter when the leaf is closing the open side of the cabinet.

50 2. In a typewriter cabinet of the upright type, including a housing having an open side and a leaf swingably secured at one of its edges to the cabinet for movement to and from a position closing said open side, a fixture for carrying the 55 typewriter comprising a platform overlying the leaf and extending to each side of the axis around which the leaf swings; means hingedly affixing one edge of said platform to the leaf; and a spring 60 joining the platform and the cabinet to draw the other edge of the platform against the latter when the leaf is closing the open side of the cabinet, said spring being positioned to be free from tension when the leaf is in a horizontal position.

65 3. In a typewriter cabinet of the upright type, including a housing having an open side and a leaf swingably secured at one of its edges to the cabinet for movement to and from a position closing said open side, a fixture for carrying the 70 typewriter comprising a platform overlying the leaf and extending to each side of the axis around which the leaf swings; means hingedly affixing one edge of said platform to the leaf; and a spring 75 joining the platform and the cabinet to draw the other edge of the platform against the

latter when the leaf is closing the open side of the cabinet, the typewriter being on that portion of the platform between said one edge and the one edge of the leaf.

4. In a typewriter cabinet of the upright type, including a housing having an inclined side provided with an opening therein and a leaf swingably secured at one of its edges to the cabinet for movement to and from an inclined position closing the opening, a fixture for carrying the typewriter comprising a platform overlying the leaf and extending to each side of the axis around which the leaf swings; means hingedly affixing one edge of said platform to the leaf between its said one edge and the opposite edge thereof; a laterally extending member at the opposite edge of the platform within the cabinet and spaced from the said one edge of the leaf; and a spring joining the cabinet and said opposite edge of the platform for holding the free end of the laterally extending member against the cabinet when the leaf is closing the opening.

5. In a typewriter cabinet of the upright type, including a housing having an inclined side provided with an opening therein and a leaf swingably secured at one of its edges to the cabinet for movement to and from an inclined position closing the opening, a fixture for carrying the typewriter comprising a platform overlying the leaf and extending to each side of the axis around which the leaf swings; means hingedly affixing one edge of said platform to the leaf between its said one edge and the opposite edge thereof; a laterally extending member at the opposite edge of the platform and projecting from one side thereof, said member being always within the cabinet and spaced from the said one edge of the leaf; a yoke on the other side of the platform and spaced from the leaf; and a spring joining the cabinet and said yoke for holding the free end of the member against the cabinet when the leaf is in position to close the opening.

6. In a typewriter cabinet of the upright type, including a housing having an inclined side provided with an opening therein and a leaf swingably secured at one of its edges to the cabinet for movement to and from an inclined position closing the opening, a fixture for carrying the typewriter comprising a platform overlying the leaf and extending to each side of the axis around which the leaf swings; means hingedly affixing one edge of said platform to the leaf between its said one edge and the opposite edge thereof; a laterally extending member at the opposite edge of the platform within the cabinet and spaced from the said one edge of the leaf; and a spring joining the cabinet and said opposite edge of the platform for holding the free end of the laterally extending member against the cabinet when the leaf is closing the opening therein, the length of said laterally extending member being sufficient to hold the platform in a substantially vertical plane when the leaf is in the inclined position closing the opening, said platform consisting of a pair of spaced apart strips, said yoke serving to secure together the strips.

7. A typewriter desk of the upright type comprising a cabinet having an inclined side provided with an opening therein; a leaf hingedly mounted on the cabinet for movement from an inclined position closing the opening to a hori- 75

zontal position and back; a platform overlying a portion of the leaf and extending into the cabinet; means hingedly joining one edge of said platform to the leaf; and structure cooperating with a wall of the cabinet for yieldably holding the platform against swinging movement about the hinge connection with the leaf when the latter is closing the opening.

5. 8. In a typewriter cabinet of the upright type, including an open-sided housing and a swingably mounted leaf movable to and from a position closing said open side, a fixture for carrying the typewriter comprising a pair of spaced apart L-shaped members having the free ends of one set 10 of legs thereof hingedly affixed to the leaf; a yoke joining the L-shaped members at the other ends of said legs; and means comprising a spring for yieldably holding the fixture in position when the leaf is in the closed position.

9. In a typewriter cabinet of the upright type, including an open-sided housing and a leaf swingably secured at one of its edges to the cabinet for movement to and from a position closing said open side, a fixture for carrying the typewriter comprising a platform overlying the leaf and extending to each side of the axis around which the leaf swings; means hingedly affixing one edge of said platform to the leaf; and a spring joining the platform and the cabinet to 15 draw the other edge of the platform against the latter when the leaf is closing the open side of the cabinet, the action of gravity on said fixture and the typewriter thereon, serving to hold the leaf in the last mentioned position with the typewriter within the housing.

ARTHUR C. THOMPSON.
